UNITED STATES PATENT OFFICE

164,437

ARTICLE SUPPORT FOR A DISPLAY STAND

Joseph D. Marquis and Frederick W. Ehlert, Chicago, Ill., assignors to Curt Teich & Company, a corporation of Illinois

Application August 8, 1950, Serial No. 11,672

Term of patent 14 years

(Cl. D80—1)

To all whom it may concern:

Be it known that we, Joseph D. Marquis and Frederick W. Ehlert, both citizens of the United States, residing at Chicago, in the county of Cook and State of Illinois, have invented a new, original, and ornamental Design for an Article Support for a Display Stand, of which the following is a specification forming part thereof.

We claim:

The ornamental design for an article support for a display stand, as shown.

JOSEPH D. MARQUIS.
FREDERICK W. EHLERT.
